WEAR COMPENSATING MEANS FOR RAIL JOINTS

Original Filed April 3, 1926

Inventor:
Robert Emmet Keough
by Frank M. Slagle
his attorney.

UNITED STATES PATENT OFFICE.

ROBERT EMMET KEOUGH, OF MONTREAL, QUEBEC, CANADA, ASSIGNOR TO THE AMERICAN FORK & HOE COMPANY, OF CLEVELAND, OHIO, A CORPORATION OF OHIO.

WEAR-COMPENSATING MEANS FOR RAIL JOINTS.

Original application filed April 3, 1926, Serial No. 99,475. Divided and this application filed December 17, 1927. Serial No. 240,685.

My invention relates to improvements in rail joint construction and relates more particularly to provision of wear compensating means for rail joints whereby rail joint 5 side bars which have become worn by the ends of the railroad rails contained within the joints, and which otherwise are sufficiently strong to meet the requirements of use, may be continued in use in connection 10 with either the same rails, worn or otherwise, or new rails.

In the practical use of rail joints the hammering down of the rail ends by the passage of the trucks of trains passing over the rails, 15 results in wear at the under sides of the rail head flanges, the surfaces of the rail joint side bars engageable therewith, and the engaging surfaces of the rail base flanges and side bars.

20 An object of my present invention is to provide a wear compensating means adaptable to be placed in the space provided by the wearing away of portions of the rail joint or the rails comprised therein, and 25 which will support the parts in their proper positions.

Another object of my invention is to provide against the longitudinal shifting of the wear compensating means of the various 30 types proposed herein, so that the wear compensating means will always be retained in that position relative to the worn portions of the rail or rail joint surfaces wherein they will most efficiently compensate for the 35 wear thereof.

Another object of my invention is to provide, as a unitary element, a wear compensating means for rail joints comprising a metallic shim insertable in the joint to compensate for wear thereof.

40 Another object of my invention is to provide a shim of unitary construction, insertable to compensate for wear in a rail joint and which will compensate for the wear at a 45 plurality of portions in the rail joint.

Other objects of my invention and the invention itself will become apparent by reference to the following description of certain embodiments of my invention and in which 50 description reference will be had to the accompanying drawings forming a part of the specification, and in which drawings:

Fig. 1 shows in elevational view an em-

bodiment of my invention applied to a rail joint;

55 Fig. 2 is a transverse section taken transversely of the rail joint of Fig. 1 at its middle and between the ends of the abutting rails.

Fig. 3 is a perspective view of a shim 60 element illustrated as embodied in the structure of Figs. 1 and 2;

Fig. 4 is an other embodiment of shim, similarly illustrated in Figs. 1 and 2;

Fig. 5 is a sectional view taken on the line 65 5-5 of Figs. 3 and 4; the view serving to illustrate like lines of section in both of the preceding embodiments;

Fig. 6 is a perspective view of a third embodiment of my invention;

70 Fig. 7 is a section taken on the line 7-7 of Fig. 6.

The rail joint of my invention comprises a pair of joint side bars which are bolted to the two sides of a pair of longitudinally 75 abutting railway rails by a plurality of rail bolts passing through the aligned perforations of the joint bars and the intermediate webs of the rails; also as later more specifically described, I provide at either or both 80 sides of the two abutting rails, shims of any of the general types illustrated herein, depending upon the amount of wear which has previously occurred on the surface of the joint bars and rails which in the operation 85 of the joint are susceptible to wear by pounding together, incidental to the passage of a train over the rail joint.

It will be understood that the shims of the various general types as herein illustrated 90 may be placed at either or both sides of any rail joint and will be made in varying thicknesses to compensate for varying degrees of wear met with in practice and desired to be compensated for by the inclusion of such 95 shims in the joint.

Referring now first specifically to the embodiments of my invention illustrated in Figs. 1, 2, 3 and 5, I illustrate therein a wear compensating means for the rail joint of 100 Figs. 1 and 2, comprising a shim of hardened steel or like material, illustrated in Figs. 3 and 5, and which is rolled or otherwise formed to be of greatest thickness in its longitudinal medial portion as indicated by the 105 line 5-5 shown on Fig. 3, and as illustrated

in section in Fig. 5, the shim being so placed in the joint that such portion of greatest thickness is adapted to contact with the clamping surface of the joint side bar and the rail upon which the greatest wear has been accomplished. From the line 5—5 of greatest thickness and towards the ends of the shim proceeding from such line of greatest thickness, the shim is preferably made of progressively less thickness, the minimum thickness being at the ends of the shim. This will provide a compensating filler for the crevice formed by the pounding of the rails on the rail joint side bars which is widest at its middle portion, generally at the ends of the rails and which tapers in breadth in portions of the joint relatively remote from the ends of the rails.

The shim of Figs. 3 and 5 is formed with an intermediate web portion 41 and angularly disposed flanged portions 42 and 43, the flanged portions being projected between the wearing surfaces of the rail joint under the rail head flange 34, Fig. 2, and above the rail base flange 20, the flanges thereby providing a facing for the rail joint side bar 2, of relatively hard metallic material, thickened intermediate its ends to compensate for the greater wear of the rail joint side bar and in some cases, also, of the rails, in intermediate portions of the joint. The web 41 performs a duo-fold purpose; first, it positions the flanges against lateral movements tending to displace them laterally of the rails; and second, by the provision for engagement between portions of the web 41 and the rail joint bolts 7, the shim is prevented from longitudinal endwise movement relative to the position of the rail ends. In the embodiment of Figs. 3 and 5, this positioning is had by virtue of the bolts 7 being projected loosely through perforations 7' of the shim, such perforations being disposed in the web of the shim and so positioned as to be alignable with the apertures 59 through the rail web and 28 of the joint side bar. The angularity of the flanges 42 and 43 may be varied, but preferably will be substantially the same as the angularity of the contacted surface of the rail head and base flanges with which the shim flanges contact.

The shim of the embodiment of Fig. 4 is like that of the embodiment previously described above except that the web 50 does not extend for the full length of the shim but extends merely for such a distance from the longitudinal medial line 5—5 as may be accommodated between the inner pair of rail joint bolts 7. The reduced web 50 of the embodiment of Fig. 4 positions the shim longitudinally of the rail joint by the engagement of its edges with the adjacent inner parallel bolts 7.

Referring now to the embodiment of my invention illustrated in Fig. 6, the descrip-

tion of the embodiment illustrated in Fig. 3 will apply for this also, the structure being very similar, except that openings 30 and 31 are provided above and below the intermediate portion of the web 36 having the bolt receiving perforations or openings 7'. This results in a saving of material over the shim of Fig. 3.

The shim of Figs. 4 to 7, inclusive, like that of the first described embodiment is preferably thickest in its medial portion adapted to be placed adjacent the ends of the rails to compensate for the greater wear in the joint adjacent such rail ends and progressively tapers in thickness to a minimum thickness at the ends of the shim disposed most remote from the ends of the rails.

This application is a division of application No. 99,475, filed April 3, 1926.

Having thus described my invention in certain embodiments, I am aware that numerous and extensive departures may be made from the embodiments herein illustrated and described without departing from the spirit of my invention.

I claim:

1. A wear compensating means for rail joints comprising a sheet metal body of channel cross sectional form comprising an intermediate web and wear compensating shim flanges extending divergently from the upper and lower portions thereof, said means insertable between a side bar of a rail joint and the rail with the upper and lower shim flanges interposed respectively between the side bar and the underside of the rail head flange and the upper side of the rail base flange, at least one of said flanges being tapered in thickness longitudinally of the joint to compensate for the increased amount of wear in the joint adjacent the ends of the rails.

2. A wear compensating means for rail joints comprising a sheet metal body of channel cross sectional form comprising an intermediate web and wear compensating shim flanges extending divergently from the upper and lower portions thereof, said means insertable between a side bar of a rail joint and the rail with the upper and lower shim flanges interposed respectively between the side bar and the underside of the rail head flange and the upper side of the rail base flange, said flanges being tapered in thickness longitudinally of the joint to compensate for the increased amount of wear in the joint adjacent the ends of the rails.

3. A wear compensating means for rail joints comprising a sheet metal body of channel cross sectional form comprising an intermediate web and wear compensating shim flanges extending divergently from the upper and lower portions thereof, said means insertable between a side bar of a

5 rail joint and the rail with the upper and lower shim flanges interposed respectively between the side bar and the underside of the rail head flange and the upper side of the rail base flange, at least one of said flanges being tapered in thickness longitudinally of the joint to compensate for the increased amount of wear in the joint adjacent the ends of the rails, said web engageable 10 with lateral surfaces of the rail joint bolts passing through the joint bars and rail web to restrain the body from longitudinal movement in the joint.

4. As an article of manufacture, a metallic liner element having wear-resisting surfaces, 15 adapted to be inserted between worn contacting portions of a pair of rails and a rail joint side bar bolted against a side of each of the rails, said element being thickened 20 toward portions thereof disposed adjacent the ends of the rails, and tapering in either direction therefrom, said liner comprising several angularly disposed portions, an upper of said portions adapted to be fitted 25 between the fishing surface of the rail head flange and the portion of the side bar contacting therewith, a lower of said portions adapted to be fitted between the bottom surface of the side bar and the upper surface of 30 the rail base flange.

5. As an article of manufacture, a liner element of a hard metallic material adapted to be inserted between worn contacting portions of a pair of rails and a rail joint side 35 bar bolted against a side of each of the rails, said element being thickened toward portions thereof disposed adjacent the ends of the rails, and tapering in either direction therefrom, said liner comprising several angularly disposed portions, an upper of said 40 portions adapted to be fitted between the fishing surface of the rail head flange and the portion of the side bar contacting therewith, a lower of said portions adapted to be fitted between the bottom surface of the side bar and the upper surface of the rail base flange, and a web portion joining the upper 45 and lower portions, said upper and lower portions being of hardened steel material and extending outwardly from the web portion, said web portion adapted to be disposed next adjacent the web of the rail, said web portion having an opening extending through its upper portion adapted to receive a projection of the side bar extending toward the portion of the rail web adjacent 50 the rail head, and having an opening extending through its lowermost portion adjacent the rail base flange contacting portion and adapted to receive a projecting portion of the bar extending towards the 55 portion of the rail web next adjacent the rail base.

6. As an article of manufacture, a liner element of a hard metallic material adapted to be inserted between worn contacting portions of a pair of rails and a rail joint side bar bolted against a side of each of the rails, said element being thickened toward portions thereof disposed adjacent the ends of 60 the rails, and tapering in either direction therefrom, said liner comprising several angularly disposed portions, an upper of said portions adapted to be fitted between the fishing surface of the rail head flange and 65 the portion of the side bar contacting there-

with, a lower of said portions adapted to be fitted between the bottom surface of the side bar and the upper surface of the rail base flange, and a web portion joining the upper and lower portions, said upper and lower portions being of hardened steel material and extending outwardly from the web portion, said web portion adapted to be disposed next adjacent the web of the rail, said web portion having an opening extending through its upper portion adapted to receive a projection of the side bar extending toward the portion of the rail web adjacent the rail head.

7. As an article of manufacture, a liner element of a hard metallic material adapted to be inserted between worn contacting portions of a pair of rails and a rail joint side bar bolted against a side of each of the rails, said element being thickened toward portions thereof disposed adjacent the ends of the rails, and tapering in either direction therefrom, said liner comprising several angularly disposed portions, an upper of said portions adapted to be fitted between the fishing surface of the rail head flange and the portion of the side bar contacting therewith, a lower of said portions adapted to be fitted between the bottom surface of the side bar and the upper surface of the rail base flange, and a web portion joining the upper and lower portions, said upper and lower portions being of hardened steel material and extending outwardly from the web portion, said web portion adapted to be disposed next adjacent the web of the rail, said web portion having an opening extending through its upper portion adapted to receive a projection of the side bar extending toward the portion of the rail web adjacent the rail head, and having an opening extending through its lowermost portion adjacent the rail base flange contacting portion and adapted to receive a projecting portion of the bar extending towards the portion of the rail web next adjacent the rail base.

8. A wear compensating means for rail joints comprising a sheet metal body of angular cross sectional form comprising a positioning and a wear compensating shim flange, said wear compensating flange insertable between the rail joint side bar and the upper surfaces of a pair of aligned rail base flanges, said wear compensating flange being 115 tapered in thickness longitudinally of the joint to compensate for the increased amount of wear in the joint adjacent the ends of the rails.

9. A wear compensating means for rail joints comprising a sheet metal body of channel cross-sectional form comprising an intermediate web and wear compensating shim flanges extending divergently from the upper and lower portions thereof, said 120 125

130

means insertable between a side bar of a rail joint and the rail with the upper and lower shim flanges interposed respectively between the side bar and the underside of the rail head flange and the upper side of the rail base flange, said flanges being tapered in thickness longitudinally of the joint to compensate for the increased amount of wear in the joint adjacent the ends of the rails,

said shim web flange having a pair of perforations therethrough, so spaced as to adapt them to receive the inner pair of adjacent rail joint bolts, to position the compensating means longitudinally of the joint.

In testimony whereof, I hereunto affix my signature this 12th day of Dec., 1927.

ROBERT EMMET KEOUGH.
